D. F. LOUDON,
HUMIDIFIER,
APPLICATION FILED MAR. 25, 1919.

1,311,701.

Patented July 29, 1919.

UNITED STATES PATENT OFFICE.

DORR F. LOUDON, OF NEW YORK, N. Y.

HUMIDIFIER.

1,311,701.

Specification of Letters Patent. Patented July 29, 1919.

Application filed March 25, 1919. Serial No. 285,007.

To all whom it may concern:

Be it known that I, Dorr F. Loudon, a citizen of the United States, and a resident of the city of New York, borough of Manhattan, in the county and State of New York, have invented a new and Improved Humidifier, of which the following is a full, clear, and exact description.

The object of the invention is to provide a new and improved humidifier more especially designed for use on steam and hot water radiators or other heating apparatus, and arranged to evaporate a large amount of water in a comparatively short time thus keeping the surrounding atmosphere charged with the proper amount of moisture. Another object is to provide a humidifier which is simple and durable in construction and arranged for convenient attachment to a radiator. Another object is to permit of readily disassembling the parts and packing the same into a small bundle for storage or shipping purposes. Another object is to permit convenient replacement of the absorbent cloth in case it becomes soiled or defective.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the humidifier in position on a steam radiator, parts being shown broken out;

Fig. 2 is an enlarged cross section of the same on the line 2—2 of Fig. 1;

Fig. 3 is a perspective view of the humidifier in a knock-down position, part of the water receptacle being shown in section;

Fig. 4 is an enlarged plan view of a portion of the absorbent cloth; and

Fig. 5 is a perspective view of a portion of the foraminous support for the cloth, the support being in inverted position.

A receptacle 10 open at the top and adapted to contain water rests on brackets 11 provided with angular flanges 12 in which screw the threaded ends 13 of supporting rods 14 provided with hooks 15 engaging abutting spacing bosses 16 on adjacent coils 17 of a steam or hot water radiator of usual

construction. The supporting rods 14 extend downwardly and rearwardly and support the bracket 11 at the rear of the radiator with a view to support the receptacle 10 and to hold the same in contact with the rear of the radiator coils 17, as plainly shown in Fig. 2. By adjusting the rods 14 relative to the brackets 11 the receptacle 10 can be raised or lowered until the top of the receptacle is practically flush with the top of the radiator coil 17.

Over the top of the radiator extends a foraminous plate 20 preferably made of stiff sheet metal, and provided at the front with a depending L-shaped supporting flange 21 with similar flanges 22 depending from the sides of the plate 20. The flanges 21 and 22 support the front and sides of a piece of wire netting or other foraminous material 75 forming a support 30 fastened in place by screws 31 screwing in the front flange 21. The rear end of the foraminous support 30 terminates a distance from the rear end of the top plate 20, and over the support 30 extends the front portion of a piece of absorbent material 35 having its rear portion extending down over the rear edge of the support 30 to hang down into the receptacle 10 and into the water contained therein to draw up the water by capillary attraction into the front portion of the absorbent material. The absorbent material is preferably formed of a piece of cloth or other woven textile fabric such as Turkish toweling or a similar open mesh fabric. The absorbent material 35 is provided with openings 36 produced during the weaving process thus preventing cutting of the threads in order to form such openings. It is understood that by the arrangement described the threads remain in unbroken continuity thus insuring a proper distribution of the water through capillary attraction. The support 30 is provided at its front with suitable hooks 37 engaging the front marginal portion of the absorbent material 35 to hold the latter securely in position on the support 30.

In order to insure a quick evaporation of the water contained in the front portion of the absorbent material 35 by the heat rising from the radiator it is desirable to keep the front portion of the absorbent material spaced from the foraminous plate 20. For this purpose use is preferably made of a rod 110 40 extending lengthwise under the plate 20 and on top of the front portion of the ab-

sorbent material 35 to space the latter from the plate 20; as plainly indicated in Fig. 2. The rod 40 is soldered or otherwise fastened to the under side of the plate 20.

5 It will be noticed that when the humidifier is in position on the radiator the receptacle 10 is supported by the brackets 11 from the radiator and the top of the receptacle 10 is approximately flush with the top of the radiator so that the rear ends of the side flanges 22 of the plate 20 rest on top of the receptacle to assist in supporting the plate 20 in a horizontal position on the top of the radiator.

5 It will further be noticed that by the arrangement described the water contained in the receptacle 10 is readily drawn up by the absorbent material 35 into the horizontal portion thereof and as this portion is under 10 the direct influence of the heat rising from the radiator it is evident that the water contained in this front horizontal portion of the absorbent material 35 is quickly evaporated.

From the foregoing it will be seen that 25 by the arrangement described a large amount of water is evaporated in a comparatively short time thus keeping the surrounding atmosphere charged with the desired amount of moisture. In case the absorbent material 35 becomes soiled or otherwise defective it can be readily removed from the support 30 and replaced by a new one.

The plate 20, the support 30 and the front 35 portion of the absorbent material 35 can be readily stored in the receptacle 10 together with the brackets 11 and supporting rods 14 for storage or shipping purposes, as plainly indicated in Fig. 3.

40 It is understood that the length of the plate 20 and that of the support 30 is less than the length of the receptacle 10 to permit of conveniently slipping the support down into the tank 10 when the latter is in position on the radiator and it is desired to use the top of the radiator for other purposes at the time.

Having thus described my invention, I 50 claim as new and desire to secure by Letters Patent:—

1. A humidifier for use on radiators, comprising an open top water receptacle, adjustable means for supporting the said recep-

tacle on the back of a radiator, the top of the receptacle being approximately flush 55 with the top of the radiator, a perforate plate provided at the under side of the front and sides with supporting flanges, of which the rear ends of the side supporting flanges rest on the top of the said receptacle, the 60 said side supporting flanges resting approximately at their middle on the top of the radiator, a foraminous support resting on the said supporting flanges, and a piece of absorbent material, the front portion of 65 which is held on top of the said foraminous support and the rear portion hangs down from the rear end of the said support and extends into the water contained in the said receptacle.

2. A humidifier for use on radiators, comprising an open top water receptacle, adjustable means for supporting the said receptacle on the back of a radiator, the top of the receptacle being approximately flush 70 with the top of the radiator, a perforate plate provided at the under side of the front and sides with supporting flanges, of which the rear ends of the side supporting flanges rest on the top of the said receptacle, the 75 said side supporting flanges resting approximately at their middle on the top of the radiator, a foraminous support resting on the said supporting flanges, a piece of absorbent material, the front of which is held 80 on top of the said foraminous support and the rear portion hangs down from the rear end of the said support and extends into the water contained in the said receptacle, and spacing means interposed between the front 85 portion of the said absorbent material and the said plate.

3. A humidifier, comprising a receptacle open at the top and adapted to contain water, adjustable brackets adapted to support the said receptacle on a radiator, a perforate plate adapted to rest on the top of the radiator and on the top of the said receptacle, a foraminous support mounted on the under side of the said plate, and a piece of 95 absorbent material having a portion stretched over the said support below the plate and having another portion extending into the said receptacle.

DORR F. LOUDON.
